UNITED STATES PATENT OFFICE

IRA D. PERRY, OF CHICAGO, ILLINOIS, ASSIGNOR TO EDNA L. MEYER, OF ROCKFORD, ILLINOIS

DOOR BUMPER AND THE LIKE

Application filed October 28, 1931. Serial No. 571,575.

This invention has to do with improvements in door bumpers and the like. The door bumpers herein disclosed are especially intended for use in connection with the doors of automobiles, but it will appear that they may also be used in connection with other doors in some instances. Inasmuch, however, as the devices herein disclosed have been designed especially with a view to meeting conditions in connection with automobile door construction and operation, I have illustrated and will describe particularly such application of the invention.

As a general rule the door frame of the automobile is so constructed as to provide a ledge facing in the direction of door closing movement and also a flange extending inwardly therefrom and parallel to the direction of door closing movement. The edge portion of the door itself is provided with a companion ledge facing in the direction of door closing movement and which approaches and seats against or towards the ledge of the door frame as the door is closed.

Generally also, in those cases in which the automobile bodies are provided with two doors on one side thereof, the door body is provided with a door stanchion or pillar located between the closing edges of the two doors and which door stanchion or pillar receives the edges of the two doors when closed.

The main object of the present invention is to provide a construction in which the sheet metal door stanchion or pillar is provided with an opening which is formed in the ledge thereof, together with a bumper block of resilient material which can be seated through said opening and will project above the surface of the ledge a sufficient distance to establish a portion which receives contact from the companion ledge portion of the door when closed; and to also provide a stirrup for supporting said bumper block in place, which stirrup is connected to and supported by the ledge of the door pillar at the position of the opening thereof so that the bumper block is effectually supported in a manner to enable it to receive the forces of pressure and

impact incident to the door closing movement.

In some cases also the inwardly extending flange is provided with an opening communicating with the position of the bumper block so that a portion of the bumper block may project through and beyond said flange opening in order to establish a door contacting surface lying parallel to the direction of door closing movement.

In some cases also the stirrup and the bumper block are so connected together that they may be considered largely as a unit, whereas in other cases they may be entirely separate and distinct from each other.

Other objects and uses of the invention will appear from a detailed description of the same which consists in the features of construction and the combinations of parts herein described and claimed.

In the drawing:

Figure 1 shows a fragmentary face view of a portion of a door pillar embodying the features of the present invention and having applied thereto a bumper block of suitable construction;

Figure 2 shows a cross section on the line 2—2 of Figure 1 looking in the direction of the arrows;

Figure 3 shows a longitudinal section on the line 3—3 of Figure 2 looking in the direction of the arrows;

Figure 4 shows a view similar to Figure 1 but illustrating a modified type of construction;

Figure 5 shows a cross section on the line 5—5 of Figure 4 looking in the direction of the arrows;

Figure 6 shows an edge view of the stirrup of Figures 4 and 5 removed from the rest of the structure;

Figure 7 shows a section on the line 7—7 of Figure 6 looking in the direction of the arrows;

Figure 8 shows a perspective view of another modified form of stirrup similar to the stirrup of Figures 4, 5, 6, and 7 with the exception that the bottom of the stirrup is provided with an opening instead of a projection or lug; and

Figure 9 shows still another modified form of construction in which the sides of the stirrup are provided with inward projections or enlargements which engage the companion edge portions of the bumper block.

- 5 In the different constructions the door pillar is provided with a ledge 20 which faces in the direction of door closing movement and with an inwardly extending flange 21
10 which lies parallel to the direction of door closing movement and is connected to the edge of the ledge. In the constructions illustrated the door pillar is also provided with an outwardly extending flange 22 lying parallel to the direction of door closing movement and connected to the opposite edge of the ledge 20.

20 In the construction of Figures 1, 2, and 3 the door pillar is provided with an opening in the ledge. There is also provided a bumper block 23 of resilient material such as rubber or the like which has a head portion 24 which extends above the position of the ledge 20 and establishes a contacting portion against which the companion ledge portion of the door seats during the door closing movement.

25 In the construction of Figures 1, 2, and 3 there is also provided a saddle 25 for holding the bumper block and supporting the same in place and receiving the forces of pressure and impact incident to the door closing movement. This saddle 25 comprises a strap of metal of generally U-shape and of width such that it can be set down through the opening in the ledge 20. The ends of the arms of this U-shaped saddle are hooked as shown at 26 and 27 so that they rest upon and are supported by the ledge 20 at the ends of the opening therein, and thus the saddle is effectively supported in a manner sufficient to receive and transmit the relatively heavy forces of pressure and impact incident to the door closing movement.

30 40 45 The strap of metal 25 has its end portions slit so that they may also be provided with burrs or locking fingers 28 and 29 of size and position to snap beneath and engage the under face of the ledge 20 at the ends of the opening therein, thus effectually locking the saddle in place and retaining it against any outward or retrograde movement incident to the jarring and other similar forces.

50 In the construction of Figures 1, 2, and 3 the saddle is more or less of a V-shape, the side walls of the saddle tapering towards each other and the bottom of the saddle being rounded so that the form of the saddle and of the bumper block is designed to conform substantially to the natural catenary form which it would assume under a uniformly loaded pressure.

55 In the construction of Figures 1, 2, and 3 the bottom of the saddle is also provided with a central opening through which there ex-

tends a lug 30 of the material of the bumper block, which lug is so formed that the bumper block is effectively retained in place within the saddle. The construction of Figures 1, 2, and 3 is also such that the head portion 24 of the bumper block projects somewhat beyond the plane of the inwardly extending flange 21 in order to establish a contacting door surface 31.

60 65 70 The bumper block and saddle already described may be conveniently moulded and vulcanized as a unit, the material of the bumper block sticking firmly to the metal of the saddle.

75 In the construction of Figures 4 and 5 the stirrup 32 is provided with substantially parallel sides; and its floor 33 is provided with a semi-perforation 34 which extends up far enough so that the material of the bumper block 35 may be vulcanized definitely thereto.

80 85 90 In the present case the door pillar opening is carried down into the inwardly extending flange 21 to the point 36 so that the material of the bumper block can be extended out through this enlarged opening to establish an enlarged door contacting surface 37 lying parallel to the direction of door closing movement as compared to the relatively small surface 31 of the previously described arrangement. In the present case also the material of the bumper block is carried down in the form of a lip or skirt 38 so as to slightly overlie the edge portion of the flange 21 at the position of the opening of the door pillar.

95 100 The stirrup shown in Figures 6 and 7 is substantially the same as that illustrated in Figures 4 and 5 with the bumper block removed therefrom.

105 The stirrup of Figure 8 is provided with an opening 39 in its floor through which a lug or projection of the bumper block may be extended.

110 The stirrup of Figure 9 is provided with the knobs or projections 40 and 41 in its walls which knobs or projections engage the side edges of the bumper block and firmly retain the bumper block against removal when the parts are set into place in the door pillar.

115 120 While I have herein shown and described certain embodiments of the features of my present invention still I do not intend to limit myself thereto except as I may do so in the claims.

I claim:

- 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955

gaging the ledge of the door pillar at the ends of the opening, and a bumper block of resilient material seated within and supported by the stirrup and extending above the projected plane of the ledge, substantially as described.

2. In a device of the class described the combination of a sheet metal door pillar comprising a sheet of metal suitably formed to provide a ledge facing in the direction of door closing movement and also an inwardly extending flange having its edge integral with the edge of said ledge, there being also an opening in the ledge extending lengthwise of the door pillar, a U-shaped strap stirrup extended through said opening and provided with lugs engaging the ledge at the ends of the opening thereof in locking fashion, and a bumper block of resilient material seated within and supported by said stirrup, substantially as described.

3. In a device of the class described the combination of a door pillar comprising a sheet of metal suitably formed to provide a ledge facing in the direction of door closing movement and also an inwardly extending flange having its edge integral with the edge of said ledge there being an opening in the ledge extending lengthwise of the door pillar, a bumper block of resilient material of suitable form and size and accommodated within said opening and a strap metal stirrup embracing said bumper block and provided with endwise extending lug portions for engagement and support by the ledge at the ends of the opening therein.
